CONTROL DEVICE FOR POWER LIFT
MECHANISMS

Howard Milton Johnston and Peder Bjerre,
Toronto, Ontario, Canada, assignors to Massey-
Harris Company, Limited, Toronto, Ontario,
Canada

Application April 15, 1938, Serial No. 202,268

7 Claims. (Cl. 97—244)

This invention relates to cultivating or seeding implements and the like and more specifically to a depth and clearance controlling device for the shovels, discs or the like of such implements.

The object of the invention is to provide a device which, in association with the power lift of a cultivator or other implement, is adjustable to control the extent of lift and drop of the shovels, discs or the like of the implement whereby adequate ground clearance of the shovels may be obtained always, regardless of the extent to which the shovels may enter the ground in operation. Another object is to provide a device of the character described which, in addition to performing the functions referred to, acts to hold against up and down movement the cultivating or drilling units at any level at which they may be positioned.

In a broad aspect, the invention comprises the provision, in association with the rock shaft through which the earth-engaging units of a cultivator or the like are raised or lowered, of means for rotating the rock shaft through a wide range of movement in either direction to raise or lower the units and means for varying the extent of such rotative movement.

The invention will be described with reference to the accompanying drawing, in which,

Figure 1 is a partial side view of a cultivator including the invention, and

Figure 2 is an enlarged sectional view showing details of the invention.

In the drawing, 1 indicates one of the two carrying wheels of the cultivator, 2 being the axle supported thereby. 3 is a square rock shaft and 4 is one of several rocker arms secured thereto. Each rocker arm has a connection at its end with a spring-pressed link 5, which is connected to a cultivator beam 6 carrying a cultivator tooth 7, which may be provided with the usual spring trip device, not shown. Pressure exerted on the beam 6 by the spring 5 is regulated by rotation of the rock shaft by usual manual means not shown. The construction thus far described is of a conventional nature and need not be referred to in detail.

Mounted on and fitting over the square rock shaft is a cylindrical bearing 8 having an integral flange 9 at one end and a detachable collar 10 at the other end, the collar being fixed by means of a pin 11 which passes through the collar, bearing and shaft. Mounted for free rotation on the bearing 8 adjacent the collar 10 is a cam member 12 having a groove or channel 13 in one face

to form opposing inner and outer cam surfaces 14 and 15.

Means for revolving the cam member about the bearing 8 and shaft 3 and for holding it in any fixed position comprises a gear segment 16, formed integral with the cam member, and a worm 17 meshing therewith. The worm 17 is carried by a shaft 18 mounted in a frame 19 supported on the bearing 8 adjacent the flange 9, a bearing ring 20 being provided between the meeting faces of cam member 12 and frame 19. The frame 19 is fixed in position by means of a connection 21 to a member 22 of the main cultivator frame. The worm 17 is actuated by rotation of the shaft 18, as by means of a crank, not shown, positioned for easy access by the operator.

A bracket 23 is fixed to the rock shaft adjacent the cam member 12 by means of a complementary clamping member 24 and bolts 25. A bell-pull lever 26 is pivotally mounted in a lower extension of the bracket 23 by means of a stud 27, and a roller 28 carried by a pin 29 in the bell-pull extends into the groove 13 of the cam member, the outer periphery of the roller having engagement with both inner and outer cam surfaces 25 14 and 15.

The lower extremity of the bell-pull is connected by means of a pitman 30 with the conventional power lift, not shown, of the cultivator.

In operation, the cam member 12 is placed in a predetermined position, by actuation of the worm 17, to obtain the desired extent of upward or downward movement of the cultivator teeth and the power lift placed in operation. The power lift, acting through pitman 30, bell-pull 26, and bracket 23, will rotate the rock shaft in either direction to obtain a lifting or lowering action of the teeth as desired, the bell-pull being fulcrumed by means of roller 28 on cam surface 15, during a lifting action, or on cam surface 14, 40 during a lowering action.

The extent of rotation of the rock shaft in either direction and the consequent extent of upward or downward movement of the cultivator teeth obviously will be determined by the position of the fulcrum point on the cam surfaces 14 and 15 with respect to the rock shaft. Thus, with the parts in the position shown in Figure 1, with the initial fulcrum point of the bell-pull in the zone of greatest distance from the rock shaft, the latter will be rotated, by a given movement of the power lift pitman through a longer arc than that possible by the same movement of the pitman if the initial fulcrum point were in a zone of less distance from the rock shaft. As previous- 55

ly indicated, the location of the initial fulcrum point is fixed by manually adjusting the cam member independently of movement of the rock shaft, and without regard to the condition of the pressure spring 5.

It will thus be observed that the structure permits a wide range of rotative movement of the rock shaft of the implement and that this range of movement is not influenced by operation of the usual means for exerting pressure on the shovels or the like to force them more deeply into the earth.

The double-acting surfaces of the cam member also act to hold firmly the rock shaft in any fixed position. Thus, should soft ground or holes be encountered by the earth-engaging units, such units will not drop but will be maintained at the determined level.

We claim:

20 1. In an implement having a wheel-supported frame, a rock shaft and a plurality of earth-engaging units mounted in said frame, said rock shaft having a connection with said units and being rotatable to raise and lower said units, 25 means for imparting rotative movement to said rock shaft comprising a pitman and a lever pivotally connected to said pitman and to said rock shaft, an adjustable member adapted to provide a fulcrum point for said lever, and means for adjusting said member to vary the position of said fulcrum point whereby the extent of said rotative movement in response to a given pitman stroke is varied.

2. In an implement having a wheel-supported frame, a rock shaft and a plurality of earth-engaging units mounted in said frame, said rock shaft having a connection with said units and being rotatable to raise and lower said units, means for imparting rotative movement to said rock shaft comprising a pitman and a lever pivotally connected to said pitman and to said rock shaft, an adjustable member having a cam surface adapted to provide a fulcrum point for said lever, and means for adjusting said member to 45 vary the position of the fulcrum point on said cam surface whereby the extent of said rotative movement in response to a given pitman stroke is varied.

3. In an implement having a wheel-supported frame, a rock shaft and a plurality of earth-engaging units mounted in said frame, said rock shaft having a connection with said units and being rotatable to raise and lower said units, means for imparting rotative movement to said rock shaft comprising a pitman and a lever pivotally connected to said pitman and to said rock shaft, a cam member rotatably mounted on said rock shaft and providing a fulcrum point for said lever,

and means for rotating said cam member and holding it in any fixed position.

4. In an implement having a wheel-supported frame, a rock shaft and a plurality of earth-engaging units mounted in said frame, said rock shaft having a connection with said units and being rotatable to raise and lower said units, means for imparting rotative movement to said rock shaft comprising a pitman and a lever pivotally connected to said pitman and to said rock shaft, 10 a cam member mounted for adjustive rotative movement on said rock shaft and having opposed cam surfaces thereon, one of said cam surfaces being adapted to provide a fulcrum point for said lever.

15 5. In an implement having a wheel-supported frame, a rock shaft and a plurality of earth-engaging units mounted in said frame, said rock shaft having a connection with said units and being rotatable to raise and lower said units, means 20 for imparting rotative movement to said rock shaft comprising a pitman, a bell-pull lever pivotally connected to said pitman and to said rock shaft, a cam member rotatably mounted on said rock shaft and providing a fulcrum point for said lever, and means for rotating said cam member and holding it in any fixed position comprising a gear segment carried by the cam member and a worm meshing with said gear segment.

6. In an implement having a wheel-supported frame, a rock shaft and a plurality of earth-engaging units mounted in said frame, said rock shaft having a connection with said units and being rotatable to raise and lower said units, means for imparting rotative movement to said rock 35 shaft comprising a pitman, a bell-pull lever pivotally connected to said pitman and to said rock shaft, an extension on said lever on which it is adapted to fulcrum, and a cam member mounted for adjustable rotative movement on said rock 40 shaft, said lever extension engaging on said cam member.

7. In an implement having a wheel-supported frame, a rock shaft and a plurality of earth-engaging units mounted in said frame, said rock shaft having a connection with said units and being rotatable to raise and lower said units, means for imparting rotative movement to said rock shaft comprising a pitman, a bell-pull lever pivotally connected to said pitman and to said rock 50 shaft, a roller carried by said lever and on which said lever is adapted to fulcrum, and a cam member mounted for adjustable rotative movement on said rock shaft, said cam member having a channel therein providing opposed cam surfaces, said roller extending into said channel and engaging said opposed cam surfaces.
